DESIGN FOR A PORTABLE ROTARY DRILL UNIT OF THE LIKE

Frithiof P. Forss, Palos Heights, Ill., assignor to
Skillsaw, Inc., Chicago, Ill., a corporation of
Delaware

Application May 29, 1947, Serial No. 139,353

Term of patent 14 years

(Cl. D54—14)

To all whom it may concern:

Be it known that I, Frithiof P. Forss, a citizen of the United States, residing in the village of Palos Heights, county of Cook, and State of Illinois, have invented a new, original, and ornamental Design for a Portable Rotary Drill Unit or the like, of which the following is a specification, reference being had to the accompanying drawing, forming part thereof.

In the drawing:

Fig. 1 is a view in side elevation of a portable rotary drill unit showing my new design.

Fig. 2 is a front view of the same.

Fig. 3 is a rear view of the same.

The dominant features of my design reside in the portions in full lines.

I claim:

The ornamental design for a portable rotary drill unit or the like, as shown and described.

FRITHIOF P. FORSS.
